UNITED STATES PATENT OFFICE.

JOSEPH D. NORRIS, OF LA PORTE, INDIANA.

CUTTER-BAR GUIDE FOR HARVESTERS.

SPECIFICATION forming part of Letters Patent No. 405,048, dated June 11, 1889.

Application filed December 20, 1888. Serial No. 294,164. (No model.)

To all whom it may concern:

Be it known that I, JOSEPH D. NORRIS, a citizen of the United States, residing at La Porte, in the county of La Porte and State of Indiana, have invented a new and useful Improvement in Cutter-Bar Guides for Harvesters, of which the following is a specification.

My invention relates to an improved construction of the guides, or "buttons," as they are also sometimes termed, employed on harvesting machinery secured to the finger-bar at intervals and extending over the back of the cutter-bar to guide it and hold it down in its reciprocating movement.

As hitherto most commonly constructed, the guide has consisted of a solid metal finger bolted or riveted to the finger-bar to extend at its forward end over the back of the cutter-bar, and the more usual manner of lubrication practiced with this construction has been to apply the lubricating medium to the cutter-bar and depend for spreading the lubricant upon the vibration of the bar in contact with the guides. This construction is objectionable for various reasons, among which may be mentioned that the lubricant is wasted to a very material extent by being wiped off the bar by the grain or grass, thereby tending to prevent the contact-surfaces of the guides with the bar from becoming thoroughly oiled, and causing the comparatively small quantity of lubricant that reaches the guides to be soon removed. Further objections to the guide thus referred to as constituting the more common form hitherto employed are that, being formed entirely of metal, it is somewhat heavy, and necessarily so, to afford the requisite strength, and by the frictional contact of the metal of the cutter-bar with that of the guides

the parts wear rapidly, and when the guides become bent upward by the strain to which they are subjected the cutter-bar strikes against them, producing clattering noise. These objections I overcome by my improvement.

My invention consists in a cutter-bar guide having a metal cap and a wooden filling.

It further consists in a cutter-bar guide formed with a metal cap and a filling within the cap provided with a lubricant-duct.

It also consists in details of construction and combinations of parts.

In the accompanying drawings, Figure 1 shows my improved guide in side elevation applied to the part of a harvesting-machine with which it is used to control the cutter-bar. Fig. 2 is a section of the guide, taken on the line 2 of Fig. 3 and viewed in the direction of the arrow, and Fig. 3 is a section taken on the line 3 of Fig. 2 and viewed in the direction of the arrow.

A is the guide, which, as shown, comprises a metal, preferably steel, cap *r* of the form illustrated or of any other suitable form, and a filling *r'*, of wood, preferably of a hard variety, and conforming in shape to the interior of the cap *r*, into which it should fit. Both the cap and filling are perforated to admit through them the securing means *q*, (bolt or rivet,) by which the guide is fastened in position, and that part of the guide which projects beyond the edge of the finger-bar and extends over the cutter-bar may be formed with an offset, as shown, and is provided with a receptacle *C* for lubricant, which, as the simplest form thereof, may comprise a concavity *o* in the upper side of the forward end of the filling, having a comparatively small perforation *n* in its base, and thus adapted to receive cotton or other material, which will absorb the lubricant and hold and supply it to the reciprocating cutter-bar. The cap *r*, where it covers the oil-receptacle, may be provided with an opening *m*, leading into the concavity *o*, and through which to supply lubricant to the receptacle for it.

I have thus described in detail what I consider to be the preferred construction of my improved device, since it affords as advantages a guide which permits ready and effective lubrication, and tends thus to prevent wear of the parts, and which is light and strong, owing to the wooden part and the cap or arched form of the covering part *r*. Further, it presents to the reciprocating cutter-bar a friction-surface of wood, being a material which is not so readily worn by the bar, and which does not so readily wear the latter as would metal, and, besides, the wood becomes itself saturated with the lubricant, and thus always insures the presentation of a well-lubricated surface to the cutter-bar.

I do not desire to be understood as limiting myself to the details of construction herein

referred to as being the preferred, as it may be readily modified without departing from the spirit of my invention, which I consider to include any cutter-bar guide formed with a cap and a filling, whether the latter be composed of metal or of wood.

What I claim as new, and desire to secure by Letters Patent, is—

1. In a guide A for the cutter-bars of harvesting-machines, the combination of a metal cap r and a wooden filling r' within the cap, substantially as described.
2. A guide A for the cutter-bars of harvesting-machines, comprising a metal cap r and a

filling r' within the cap provided with a lubricant-receptacle, substantially as described.

3. A guide A for the cutter-bars of harvesting-machines, comprising a cap r , provided with a perforation m near one end, a wooden filling r' within the cap, having a concavity o coincident with the perforation in the cap, and an opening n in its base, substantially as described.

JOSEPH D. NORRIS.
